UNITED STATES PATENT OFFICE.

LEWIS JONES, JR., OF PHILADELPHIA, PENNSYLVANIA.

IGNITER FOR EXPLOSIVE-ENGINES.

SPECIFICATION forming part of Letters Patent No. 645,398, dated March 13, 1900.

Application filed June 22, 1899. Serial No. 721,501. (No model.)

To all whom it may concern:

Be it known that I, LEWIS JONES, Jr., of Philadelphia, in the State of Pennsylvania, have invented certain new and useful Improvements in Igniters for Explosive-Engines, whereof the following is a specification, reference being had to the accompanying drawings.

My invention relates to igniters comprising relatively-movable terminals of an electrical circuit and means to produce an electrical spark between said terminals by the contact and separation thereof.

It is the object of my invention to provide a durable and efficient device of the type specified consisting of few and simple parts arranged to be readily removed and returned with respect to their operative position in an explosive-engine, so as to be conveniently repaired or renewed.

In the accompanying drawings, Figure 1 is a sectional view showing a convenient embodiment of my invention. Fig. 2 is an inverted plan view of the removable plug in which the electrical terminals are mounted. Fig. 3 is a perspective view showing the construction of the terminal-actuating mechanism.

In said figures, A is the engine-cylinder, which is in communication with the gas-chamber B, whose wall b is provided with a screw-threaded opening b', in which is fitted the screw-threaded plug C, containing the terminals D and E of an electric circuit comprising a source of current. The terminal D extends within said gas-chamber B in fixed insulated relation with said plug, and the contact-lug d of said terminal D is opposed to the contact-lug e of the terminal E, which projects within said gas-chamber and is mounted to slide within said plug. The tubular extension C' upon the top of the plug C surrounds the outer extremity of the slidable terminal E and contains a spring F, which tends to thrust said terminal E into contact with the terminal D.

The rock-shaft G extends within the gas-chamber B and is provided with a tappet g, extending across the axis of rotation of the plug C. Said shaft G and tappet g are oscillated, as hereinafter described, to permit the terminal E to slide into contact with

the terminal D and to uplift it from contact therewith, and it is to be noted that the terminal E is arranged in concentric relation with the threaded portion of the plug C, 55 so that the tappet g shall always be in registry with said terminal regardless of the rotary position of said plug. Such an arrangement of the terminals is advantageous in that it facilitates the assembling of the parts. The 60 tappet H is fixed upon said shaft G exterior to said chamber and is provided with the arm I and spring J, which serve to normally maintain the terminal E uplifted in the position shown in Fig. 1. The outer end h of said 65 tappet H projects within the path of the cam-piece K, which is mounted upon the cam-disk L, fixed upon the rotary shaft M, the relation of the parts being such that said tappet F is uplifted by the traverse of the cam-piece K 70 beneath its outer end h to permit the terminal E to be thrust into contact with the terminal D by means of the spring F. When, however, the corner k of said cam-piece K escapes from beneath the tappet end h, the latter is snapped back into its normal position by means of the spring J, and, the terminal E being thereby uplifted and separated from the terminal D, a spark is produced between the respective terminal-lugs d and e and the 80 gas within said chamber B is ignited. There is a definite and substantially-uniform lapse of time between each production of the electric spark at said terminals D E and the consequent explosion within the cylinder A, so 85 that if the spark is produced at the instant the piston in the cylinder comes to rest at the extremity of its stroke there is some idle motion of the parts before the effective explosion occurs, and therefore when the engine 90 is running at full speed it is desirable to operate the igniter before the instant of rest of said piston, so that the effective explosion shall occur at the proper time and the maximum efficiency of operation be secured. 95 When, however, the parts are fixed in the position required for most efficient operation at full speed, the explosion may occur prematurely when the engine is first started or is moving at slow speed. Therefore I find it 100 advantageous to provide means to adjustably vary the instant of production of the spark

with respect to the cycle of operation of the engine, and it being understood that the shaft M is always rotated in definite relation with the movement of the engine-piston such variation in the production of the spark is conveniently effected as follows: A supplemental bearing member N is pivoted at n upon the bearing end h of the tappet H to form, in the position of the parts shown in Fig. 1, a continuation of said bearing end h of the tappet to uphold the latter by contact with the cam-piece K until said cam and the shaft M are rotated to a greater extent than is required to free the end h from said cam-piece. Said supplemental tappet member N is formed of such thickness as to delay the operation of the igniter the proper length of time to insure the maximum efficiency of the engine when starting or running at slow speed. When, however, the speed of the engine is increased, the member N may be rotated out of alinement with the tappet end h, as shown in Fig. 3, and the cam-piece K having to traverse merely the narrow extent of said end h the spark is produced at an earlier instant in the cycle of operation of the engine and the maximum efficiency thereof at high speed is secured. Instantaneous separation of the terminals D E being necessary to secure the maximum efficiency of production of an electric spark between them, the corner k of the cam-piece K is formed substantially radial with respect to the shaft M, and the bearing end h of the tappet H and its supplement N are also abruptly terminated. Although it is designed that the shaft M shall be continuously rotated in the direction indicated by the arrow upon Fig. 1 in order to prevent destruction of the tappet or cam-piece by possible reverse engagement of the abrupt edges thereof, I prefer to pivot the cam-piece K upon the cam-disk L and maintain it normally against the stop l, as shown, by means of the spring m, so that if the cam-disk is reversely rotated said cam-piece K shall clear the tappet by idly rotating upon its pivotal bearing k' against the tension of said spring m, the latter, however, serving to instantly return the cam-piece to its normal position when released.

I do not desire to limit myself to the precise details of construction or arrangement of the parts which I have described, as it is obvious that various modifications may be made therein without departing from the spirit of my invention.

I claim—

1. In an igniter for an explosive-engine, the combination with a gas-chamber, having a screw-threaded aperture in its wall, of a screw-threaded plug, fitted to said aperture, an electrical terminal mounted in said plug, in eccentric relation with said thread, an electrical terminal mounted to slide in said plug in concentric relation with said thread, and a rock-shaft having a tappet within said chamber, arranged in concentric relation with said

screw-thread, to operate said concentric slideable terminal, substantially as set forth.

2. In an igniter for an explosive-engine, the combination with a gas-chamber, having an aperture in its wall, of a plug fitted to said aperture, an electrical terminal mounted in said plug, in eccentric relation therewith, an electrical terminal mounted to slide in said plug, in concentric relation therewith, and a rock-shaft having a tappet arranged in concentric relation with said plug, to operate said concentric slideable terminal, substantially as set forth.

3. In an igniter for an explosive-engine, the combination with a gas-chamber, of an igniter-plug entered in the wall of said gas-chamber, in removable relation therewith, an electrical terminal fixed in said plug, an electrical terminal mounted to slide in said plug, a rock-shaft provided with a tappet within said chamber, in operative relation with said slideable terminal, a tappet fixed upon said rock-shaft exterior to said chamber, a rotary cam-disk arranged to oscillate said tappet, and means, adjustably mounted upon said exterior tappet, arranged to vary its oscillation, substantially as set forth.

4. In an igniter for an explosive-engine, the combination with a gas-chamber, having a screw-threaded aperture in its wall, of a screw-threaded plug fitted to said aperture, an electrical terminal fixed in said plug in eccentric relation with said thread, means to insulate said eccentric terminal from said plug, an electrical terminal mounted to slide in said plug in concentric relation with said thread, a tubular extension of said plug, exterior to said gas-chamber, inclosing said slideable terminal, a spring arranged in said tubular extension to thrust said slideable terminal inwardly, a rock-shaft provided with a tappet extending within said chamber, in registry with said concentric terminal, a spring, operatively related to said shaft, to normally uplift said concentric terminal, by means of said tappet, and means to oscillate said rock-shaft and thereby effect the connection, and disconnection, of said terminals, substantially as set forth.

5. In an igniter for an explosive-engine, the combination with a gas-chamber, having a screw-threaded aperture in its wall, of a screw-threaded plug fitted to said aperture, an electrical terminal fixed in said plug in eccentric relation with said thread, means to insulate said eccentric terminal from said plug, an electrical terminal mounted to slide in said plug in concentric relation with said thread, a tubular extension of said plug, exterior to said gas-chamber, inclosing said slideable terminal, a spring, arranged in said tubular extension to thrust said slideable terminal inwardly, a rock-shaft provided with a tappet extending within said chamber, in registry with said concentric terminal, a spring, operatively related to said shaft, to normally up-

lift said concentric terminal, by means of said tappet, a second tappet upon said rock-shaft, exterior to said gas-chamber, an adjustable supplemental bearing member, pivoted upon

5 said exterior tappet, a rotary cam-disk, a cam-piece eccentrically pivoted upon said cam-disk, in operative relation with said exterior

tappet, a stop upon said cam-disk, and a spring to normally maintain said cam-piece against said stop, substantially as set forth.
